WILLIAM C. ROE, OF PITTSBURGH, PENNSYLVANIA, ASSIGNOR OF ONE-HALF TO
WILLIAM C. HANDLAN, OF WHEELING, WEST VIRGINIA.

TRAIN-CONTROL SYSTEM FOR TOY RAILWAYS.

1,327,215.

Specification of Letters Patent.

Patented Jan. 6, 1920.

Application filed September 27, 1919. Serial No. 326,746.

To all whom it may concern:

Be it known that I, WILLIAM C. ROE, a citizen of the United States of America, and resident of Pittsburgh, county of Allegheny, and State of Pennsylvania, have invented certain new and useful Improvements in Train-Control Systems for Toy Railways, of which the following is a specification.

10 This invention relates broadly to a system of electrical train control for toy railways, and it has for its primary object to provide, in association with a toy railway and a train or locomotive designed for 15 travel thereon, a construction and arrangement of electrical equipment whereby said train or locomotive may be propelled and whereby the direction of travel thereof may be controlled from a point remote with respect thereto.

20 A further object is to provide a system of train control in which the reversal of the direction of travel is effected automatically by the mere act of opening the electrical circuit for a brief interval of time—that is, by opening a switch in said circuit and then restoring the circuit by closing said switch.

25 Another object is to provide a system of the character mentioned which is operative either on alternating or direct current and which may be arranged to operate either with a two-wire or three-wire control.

30 A still further object is to improve the train control system disclosed in my United States Letters Patent No. 1,259,135, granted March 12, 1918.

35 In describing the invention in detail, reference is herein had to the accompanying drawings, in which—

Figure 1 is a sectional elevation of the train-carried driving motor;

Fig. 2 is a diagrammatic view of the system; and—

40 Fig. 3 is a similar view of a modified arrangement.

45 Referring first to Figs. 1 and 2 of said drawings, A indicates generally a multi-polar motor carried by a train or locomotive and designed to drive the latter through suitable gearing associated with the drive-shaft 1 upon which is mounted the armature 2 and commutator 3. Associated with said armature is a field magnet 4 the field 4^a

of which is provided with differential windings 5 and 6 which are connected to one brush, as 7, of said commutator by a common conductor 8. Said windings 5 and 6 are respectively connected by conductors 9 and 10 to two opposed contacts 11 and 12 60 carried at suitable points in more or less closely associated relation.

The opposite commutator brush 13 is suitably connected, as by a conductor 14, to an axle 15 of the locomotive or train 65 and through said axle and a wheel 23 to a track rail 16 to which a conductor 17 leads from a suitable source of electric current, as a storage battery 18. Leading to the opposite track rail 19 from the opposite 70 pole of said battery or other current source is a conductor 20.

Said track rail 19, which is suitably insulated from the rail 16, as by insulation 21 interposed between it and the underlying 75 crossties 22, serves to conduct current to the wheel 24 opposite said wheel 23, whence the current is suitably conducted, as by a conductor 25, to a laterally shiftable member 26, said wheel being insulated from its axle 80 15 as indicated at 27, Fig. 2.

The shiftable member 26 is disposed between the contacts 11 and 12 and is adapted to be shifted into engagement with either of the latter, as will presently be explained, 85 for completing the electric circuit through one or the other of the windings of the differentially-wound magnet field 4^a. The free end of said shiftable member is of yoke form and has the opposite yoke members received in an annular groove or channel 28 provided therefor in the hub 29 of a fly wheel 30 which is rotatably mounted upon an end of the drive shaft 1 of the motor. Formed in said hub is a spiral 90 slot 31 of suitable length, and extending outward through this slot is a stud or pin 32 carried by said drive shaft.

In practice, the motor is driven by closing of the electric circuit, effected through the closing of a switch 33 located at any convenient point in said circuit, in a direction controlled by the direction taken by the current in passing through the magnet field 4^a, said direction obviously depending upon 105 which of the contacts 11 or 12 is engaged by the shiftable member 26. Assuming that when the member 26 engages the outer con-

tact 11, as shown in Fig. 1, the motor will be rotated in a direction for propelling the train forward, it is obvious that a reversal of the direction of travel will be effected by shifting said member into engagement with the opposite contact 12. Such a reversal is effected automatically through a momentary opening of the electric circuit in a manner which will be now explained.

10 During forward rotation of the motor, the fly wheel 30 is rotated forward with the shaft 1 upon which it is mounted, the stud 32 fixed on said shaft being disposed at the inner end of the spiral slot 31 in the hub 29 of said fly wheel. So disposed, said stud maintains the fly wheel in the outwardly thrust position shown in full lines in Fig. 1, maintaining the member 26 in engagement with contact 11. When the motor is stopped 15 by opening the switch 33, the momentum of the fly wheel acts to cause the latter to overrun the speed of the shaft 1 and to rotate on the latter until the stud 30 seats at the opposite, or outer, end of the slot 31. As is obvious, during the overrunning movement the fly wheel is shifted inward along said shaft due to the spiral disposition of said slot, and this results in the member 26 being moved inwardly to the dotted line position indicated in Fig. 1 in which it engages the inner contact 12. It follows, therefore, that upon a restoration of the circuit, effected through reclosing of the switch 33, the motor will be actuated to rotate its shaft 1 in a reverse 20 direction.

Manifestly, the motor may be again stopped and actuated in a forward direction by the mere act of opening and again closing the switch 33, the member 26 being shifted outward into engagement with contact 11 during any interval of opening of the circuit, no matter how brief, by the overrunning movement of the fly wheel which occurs during such interval.

45 Referring to the modification illustrated in Fig. 3, a manually shiftable switch 33^a associated with a three-wire control is substituted for the automatic shifting mechanism and two-wire control hereinbefore described, said switch being shiftable into engagement with either of two contacts 34 or 35 according as it is desired to drive the train in a forward or reverse direction. Said contacts 34 and 35 are respectively connected by conductors 36 and 37 to the opposite track rails 16^a and 19^a one of which is suitably insulated. A third rail 38, also insulated, is connected by a conductor 39 to the pole of the battery 18^a opposite that which is connected by conductor 20^a to the switch 33^a. A brush 40 carried by the train and connected by a conductor 41 to a commutator brush 13^a is designed to make wiping contact with said third rail. The differential windings 5^a and 6^a of the magnet are respectively

connected by conductors 9^a and 10^a to wheels of the locomotive which travel upon said track rails 16^a and 19^a.

When the switch 33^a is disposed in engagement with contact 34 a circuit is completed through magnet winding 5^a, said circuit consisting of battery 18^a, conductor 20^a, switch 33^a, conductor 36, track rail 16^a, wheel 23^a, axle 15^a, conductor 9^a, magnet winding 5^a, conductor 8^a, brush 7^a, commutator 3^a and armature 2^a, brush 13^a, conductor 41, brush 40, third rail 38, and conductor 39. On the other hand, when the switch engages contact 35, a circuit is established through magnet winding 6^a, the same consisting of battery 18^a, conductor 20^a, switch 33^a, conductor 37, track rail 19^a, wheel 24^a, conductor 10^a, magnet winding 6^a, conductor 8^a, brush 7^a, commutator 3^a and armature 2^a, brush 13^a, conductor 41, brush 40, third rail 38, and conductor 39. 75 80 85

What is claimed is—

1. The combination with a vehicle, of an electric motor carried by said vehicle for driving the latter and embodying a field magnet with differential windings, a multi-polar armature and a commutator, a stationary source of electric current, conducting means leading from said current source to said motor, and shiftable means whereby the current is directed through either one of said magnet windings for controlling the direction of travel of the vehicle. 90 95

2. The combination with a vehicle, of an electric motor carried by said vehicle for driving the latter and embodying a field magnet with differential windings, a multi-polar armature and a commutator, a source of electric current located at a point remote from said vehicle, means for conducting an electric current from said current source to said motor, and shiftable means whereby the current through one of said magnet windings may be cut off and directed through the other of said windings for reversing the travel. 100 105 110

3. The combination with a vehicle, of an electric motor carried by said vehicle for driving the latter and embodying a field magnet with differential windings, a multi-polar armature and a commutator, a source of electric current located at a point remote from said vehicle, means for conducting an electric current from said current source to said motor, and shiftable means automatically actuated upon the breaking of the circuit through one of the magnet windings to move to a position wherein the circuit, when reclosed, includes the other of said windings. 115 120 125

4. The combination with a vehicle, of an electric motor carried by said vehicle for driving the latter and embodying a field magnet with differential windings, a multi-polar armature and a commutator, a source 130

- of electric current located at a point remote from said vehicle, means for conducting an electric current from said current source to said motor, a pair of separated contacts associated with the differential windings of the magnet, a member shiftable between said contacts and adapted to direct current through one or the other of said windings according as it engages one or the other of 5 said contacts, and means actuated upon the opening of the electric circuit through one of said windings, to automatically shift said member from engagement with one of said contacts into engagement with the other 10 whereby the circuit, when reestablished, includes the other of said windings.
5. The combination with a vehicle of an electric motor carried by said vehicle for driving the latter and embodying a magnet 15 having a differentially wound field, a multipolar armature and a commutator, said armature having a stud fixed upon its shaft adjacent to one end of the latter, a source of electric current, means for conducting current from said current source to said motor, a fly wheel having a hub provided with a spiral slot therein, said wheel being rotatable upon said armature shaft and having 20 said stud received in the slot of its hub, a pair of separated contacts associated with the differential windings of the magnet, a member disposed for movement between said contacts, said member having a part suitably connected to the fly wheel whereby it is actuated by sliding movement of said fly wheel along said armature shaft to move from en- 25 gagement with one of said contacts into engagement with the other, said stud and said slot coöperating to cause shifting movement of the fly wheel, when the motor is stopped, 40 through overrunning speed of the fly wheel due to momentum of the latter.
6. The combination with a multipolar motor having a differentially wound magnet field, and an electric circuit in which said motor is located, of means automatically actuated by opening and reclosing of said circuit whereby the current is shifted from one of the magnet windings to the other for reversing the motor; said means comprising 45 a fly wheel mounted for rotation on the armature shaft of the motor and adapted to be shifted laterally along said shaft, said wheel having a hub with a spirally disposed slot therein, and a radial stud carried by 50 said shaft disposed in said slot and adapted to actuate said fly wheel to shift along said shaft when the speed of the latter drops below that of said fly wheel; separated contacts connected to said magnet windings, 55 and a switch member associated with said fly wheel hub and adapted to be carried by shifting movement of the latter from engagement with one of said contacts into engagement with the other. 60
